CLAIM

The ornamental design for a stadium seat cushion, substantially as shown and described.

DESCRIPTION

FIG. 1 is a perspective view of the stadium seat cushion featuring a contoured top face and a bottom edge with a pattern outline showing my new design.

FIG. 2 is an alternate perspective view showing the bottom surface; and,

FIG. 3 is a top plan view.

The broken lines shown in the figures form no part of the claimed design.

1 Claim, 3 Drawing Sheets---
